DEVICE FOR CLEANING AND MIXING PAINT
AND THE LIKEJohn E. Schroder, Worcester, Mass., assignor of
one-half to Wesley E. Mellquist, Worcester,
Mass.

Application September 5, 1939, Serial No. 293,447

3 Claims. (Cl. 74—74)

This invention relates to an apparatus for cleaning paint brushes or analogous articles and for mixing materials of various kinds.

Objects of the invention include the provision of means whereby a used brush or other article may be completely freed or cleansed of paint or other material desired to be removed, in the space of a few seconds, or whereby various paints or other materials may be quickly and easily mixed; the provision of a container for holding the paints to be mixed or the paint removing liquid, and a brush or paddle holder associated therewith, together with means to rotate a brush or paddle in one direction and means to suddenly and forcefully reverse said rotation to effect a rapid oscillation of the parts, this action being continued as long as desired or necessary; and the provision of means whereby the brush or paddle may be oscillated in the absence of the material in the container without removing said material from the container.

Other objects and advantages of the invention will appear hereinafter.

Reference is to be had to the accompanying drawing, in which

Fig. 1 is a top plan view of the device;

Fig. 2 is a side elevation of the device with parts broken away;

Fig. 3 is a view in section of the device showing the brush actuating mechanism in its raised position in broken lines;

Fig. 4 is a section on line 4—4 of Fig. 3;

Fig. 5 is a detail view of the spring and its housing looking in the direction of arrow 5 in Fig. 3; and

Fig. 6 is a detail view of the face of the mutilated gear.

In the drawing, there is shown a cylindrical container 10, open at the top, and adapted to receive the paint removing liquid or materials to be mixed, as at 12. The container 10 is provided with a flange 14 to seat and position a plate 16, which acts as a top closure for the container. The plate 16 is provided with a flange 18 which closely fits the inside walls of the container; and a cylindrical shield 20 of light metal or other material is dependently secured to the flange 18 so as to extend down into the container 10, as is clearly shown in Fig. 3.

Adjacent its center, the plate 16 is provided with a bored boss 22 receiving and journaling a vertical shaft 24 having a bevel gear 26 pinned at its upper end and a generally cylindrical member 28 pinned at its lower end. The member 28 is shaped to receive the handle of a brush or

paddle 30 at its lower end, the brush or paddle extending into the liquid 12, and being held in place by thumb screws 32.

The bevel gear 26 rests on a plate 34 which is bolted or otherwise secured to the plate 16. Plate 34 supports and is bolted to a housing 36 which contains a long flat spring 38, wound around the gear 26 and pinned thereto at one end and at its other end to the housing 36. The spring 38 obviously continuously urges shaft 24 in a clockwise direction as seen in Fig. 5, this spring being under tension even when idle.

The plate 34 also mounts a boss 40 having a shaft 42 journaled therein, said shaft having a crank-handle 44 fixed to one end and a mutilated bevel gear 46 fixed to its other end and meshing with gear 26 at its tooth portion 48. A housing 50 covers gears 26 and 46. Of course, a motor could be substituted for the handle 44.

As seen in Fig. 4, the cylinder 28 is provided with a radially extending lug 52, and the underside of plate 16 has a screw-threaded lug 54 secured thereto with a screw 56 extending therethrough. The screw 56 may be adjusted longitudinally and locked by nut 58.

A plurality of rods 60 are secured in any convenient manner, as by bolts 62, adjacent the edge of the plate 16. These rods extend longitudinally of the container 10 for a considerable distance, as shown in Fig. 2. Upon raising plate 16 and the parts carried thereby, including the shield 20, the rods 60 may be aligned with sockets 64 and set therein, whereby the plate 16 and its associated parts are supported above the container 10, and the brush or paddle 30 is raised clear of the liquid 12.

In the operation of the device, the top plate 16 and its connected parts are removed from the container 10 and a desired amount of paint removing liquid, turpentine, or materials to be mixed, is placed therein. The brush or paddle 30 is secured to the member 28 by the screws 32 and the plate 16 is placed on the top of container 10 in position as shown in Fig. 3. The crank-handle 44 is turned so as to actuate gear 26 through the mutilated gear 46, thus turning the member 28 against the tension of spring 38. When the toothless portion of gear 46 is reached, in the rotation of said gear, the spring 38 is free to act, and reverses the direction of rotation of the member 28. Due to the large number of turns of spring 38, the member 28 may be placed under tension at all times, so that the increase of tension caused by the turning of the gears is large enough to reverse the rotation of the brush

or paddle with great force, and the holder 28 flies back with great speed, thus completely permeating the brush with the liquid 12, or if a paddle is used, the result will be to violently agitate the materials in the container.

The screw 56 provides an abutment and rest for the lug 52 on the member 28, and when the device is idle, the spring will keep the lug and screw in engagement, and it is clear that the gear 26 will always return to its original position. In 10 case the teeth 48 of gear 46 do not mesh easily with the teeth of gear 26, a slight adjustment of screw 56 will shift the idle position of gear 26 enough to bring about the desired location for easy meshing.

After sufficient oscillation of the brush or paddle 30 to accomplish the purpose desired, the plate 16 and its associated parts, including the shield 20 and the brush or paddle holder 28, are raised up to broken line position, as shown in Fig. 3, and the ends of the rods 60 are set in 20 sockets 64. In this position the brush or paddle 30 is clear of the material 12, and the handle 44 may be actuated again to dry the brush or paddle in the air by centrifugal force. The shield 20, overlapping the edge of the container 10, prevents splashing of the liquid so that all the liquid or other material is retained in the container.

It will be seen from the foregoing that this invention provides a device for the easy and extremely rapid cleaning of paint brushes or analogous articles, and for easy and convenient mixing of materials.

Having thus described my invention and the 30 advantages thereof, I do not wish to be limited to the details herein disclosed, otherwise than as set forth in the claims, but what I claim is:

5 1. In a device of the class described, a plate, a shaft journaled in said plate and having a gear fixed thereto at one end and an element fixed thereto at its other end, an interrupted gear in intermittent mesh with said first gear, means to rotate said interrupted gear, a long resilient member fixed to said first gear and to a fixed point and wound a plurality of times about said shaft, a lug on said element, and an adjustable abutment in the path of said lug, whereby the idle position of said first gear may be adjusted.

15 2. In a device of the class described, a flat plate-like support, a shaft journaled on said support, a second shaft journaled on said support and extending therethru, an element attached to the extending end of said second shaft, gearing including a mutilated gear between said shafts, a flat spring wound upon itself and about said second shaft and having one end secured to said shaft and the other end secured to said support, a radial projection on said element, and an abutment on said support in the path of said projection.

25 3. In a device of the class described, a generally plate-like support, a shaft journaled thereon, a mutilated bevel gear attached to the other end of said shaft, a second shaft extending thru said support and mounting an element, a bevel gear on said second shaft adapted to mesh intermittently with said mutilated gear, resilient means to operate said second shaft in a direction reverse to that of said gears, said spring comprising a flat strip of spring metal secured at one end to said shaft and at the other end to said support, and wound a plurality of times about said second shaft, and adjustable stop means for the reverse operation of said second shaft.

JOHN E. SCHRODER.
